UNITED STATES PATENT OFFICE.

PHILIPP ROSENTHAL AND WACLAW PETRAN, OF MOSCOW, RUSSIA.

MACHINE FOR CORKING BOTTLES WITH CORKS COVERED WITH PIECES OF PARCHMENT-PAPER OR THE LIKE.

SPECIFICATION forming part of Letters Patent No. 783,593, dated February 28, 1905.

Application filed July 20, 1904. Serial No. 217,384.

To all whom it may concern:

Be it known that we, PHILIPP ROSENTHAL, a subject of the King of Prussia, Emperor of Germany, and WACLAW PETRAN, a subject of the Emperor of Russia, residing at Moscow, Russia, have invented certain new and useful Improvements in Machines for Corking Bottles with Corks Covered with Pieces of Parchment-Paper or the Like; and we do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to machines for inserting stoppers in bottles; and it consists, essentially, of a corking-machine having a single driving-shaft, from which are driven co-operative mechanisms for feeding corks to the stopper-inserting plunger, for cutting from a suitable strip of material wafers to cover the cork, and means to shift each wafer after it has been cut under the cork to be inserted into the bottle, all operated by means of a single main driving-shaft preferably, but not necessarily, driven by hand, together with details of construction to be hereinafter particularly described, and pointed out in the claims.

Referring to the drawings, in which like parts are similarly designated, Figure 1 is a side elevation, Fig. 2 a front elevation, and Fig. 3 a longitudinal section, of the machine. Fig. 4 shows the wafer-transfer plate in side elevation and plan. Fig. 5 is an elevation and section of the cam. Fig. 6 is an elevation and plan of eccentric and cork-feeder. Fig. 7 illustrates a construction of the wafer punch or cutter, and Fig. 8 illustrates a wafer having serrated edges and produced by said punch.

On a suitable standard 1 is removably secured a casing 2, of cast-iron or other suitable material, in which is mounted a main shaft 3, on which are fixed the worm 6 and fly-wheel 5 at one end, preferably, but not necessarily, operated by hand-power. On the other end

of the shaft 3 is another worm, 20, by which the mechanism for drawing the strip of material after the wafers have been cut therefrom is operated and hereinafter described.

The worm 6 drives a worm-wheel 7, fast on a shaft 4, transversely of the main driving-shaft 3. The shaft 4 has a crank 9 at one end connected by rod 10 to the upper end of the plunger 11, that is guided in the cylinder *c*, and whose reduced end *b* engages a cork positioned to be inserted into the bottle. On the cylinder *c* is an open-ended tubular magazine 42, that holds a supply of superposed corks, the lowermost of which rests on the table 46 immediately in front of the liner 12. This liner has a conical opening through it for the purpose of compressing the cork as it is forced through it by the reduced end *b* of the plunger, and at the back has a projection 47. Within the boss *d*, projecting below the table 46, is a sleeve *e*, containing a spring 65, that holds the shoulder *f* of the liner 12 normally against the table 46. The sleeve *e*, between which and the liner 12 is the spring 65', is held in place by the lower removable end 66', Fig. 2, of the corking mechanism, which in turn is secured in place by screws 68. The lower end 66 of the corking mechanism has a slot *g* for the entrance of the recessed forked end of the wafer-shifting device 35.

On the main shaft 3 is an eccentric 44, that operates an eccentric-rod 43, connected at its free end to the lower end of a rod 49, pivoted at *h*, which rod carries a gripper 45, the enlargement 48 of which moves under the lower open end of the magazine 42 as the cork on the table 46 is pushed against the semicircular projection 47 of the liner, thus preventing the superposed corks in the magazine from descending until the gripper has been again moved out from under the magazine.

The shaft 4 has at the end opposite the crank 9 a gear-wheel 39, that drives a pair of gear-wheels, one wheel, 58, of which is keyed to one end of and drives a shaft *i*, and the other end of this shaft carries a roll 56, having a segmental enlargement 57, that at every revolution contacts with a roll 55. These two rolls

act as drawing-off rolls and draw the strip of paper 14 step by step from the roll of paper supported on a spindle *k* of a bracket *l*, fixed on the machine, and feed the paper forward in like manner. The paper then passes from the drawing-off rolls through a guideway 15, Fig. 2, under the wafer-cutting mechanism. This wafer-cutting mechanism comprises a boss 16, having an internal configuration, substantially as shown, and contains a clamping-cylinder 23, having internally-projecting pins 32, that pass through longitudinal slots 33 in the punch 24, and between these pins 32 and the closed upper end of the cylindrical punch 24 is a spring 31, so that both punch and clamping-cylinder will move in unison and at the same time permit a further independent downward movement of the punch to enable it to pass through the paper strip. The hollow tubular shank 24' of the punch is surrounded by a spring 27, acting on a perforated cap 28 and normally holding the punch in its uppermost position. Within the hollow tubular shank 24' of the punch is a piston 30, acted upon by a spiral spring 29, holding the piston normally against the cap 28. A rod or stem 26, to which the piston 30 is secured, passes through the perforation in the cap 28 and extends centrally through the cutter 24 and carries at its lower end an expelling-disk 25 just above the slot 17, through which the paper strip passes. A nut 69 secures the parts of the cutting device in the boss 16 and is provided with a slot through which the wafer-carrying device 35 slides, and 70 is a lock-nut. On the shaft 4 adjacent the crank-arm 9 is a cam 8, having a slot *m*, in which is mounted a roller 34, said cam acting upon the cap 28 to depress the cutter and the roller 34 acting on the stem 26 of the expelling-disk 25 to depress this disk after the cutter has been depressed. All the cutter mechanism is thus operated from the shaft 4, that drives the stopper-inserting mechanism, while the stopper-positioning mechanism to position the stoppers ready for operation upon them by the stopper-inserting mechanism is operated from the main driving-shaft.

After the wafer has been cut from the paper strip the remainder of the strip passes between the aforementioned drawing-rolls operated from the main shaft, consisting of a roll 18, mounted on a shaft *o*, on which is mounted the previously-described worm-wheel 21. Said roll 18 has a sector-shaped enlargement 22, that at each revolution of the roll 18 and shaft *o* contacts with the strip between it and a roll 19 to draw the strip 14 step by step—that is, after each wafer has been cut from said strip—from under the cutter, so as to present a new portion of the strip to the cutter for the next wafer.

As above stated, the gear 39 on shaft 4 drives a pair of gear-wheels 40 and 58. The gear-wheel 40 is mounted loose on a shaft 41,

fixed in the frame of the machine, and is keyed or otherwise rigidly connected to a drum 38, likewise loose on said shaft 41. This drum is provided with a cam groove or way 37, in which rides a roller 60, on the upper end of a screw-stud 53, secured in the heavier portion of the wafer-carrying device. This wafer-carrying device consists of a thick plate 35, having secured thereto a thinner plate 135, having a forked recessed end. The inner end of the forked portion is circular, as shown at 59, Fig. 4, and provided with a bead 36, on which the wafer seats, so as to be below the upper surface of the plate 135 and prevent any accidental displacement of the wafer as it is carried from the cutter to a position between the liner and bottle-mouth under the cork and plunger. This reciprocation of the wafer-carrier is accomplished by the roller 60, traveling in the helical groove 37 of the drum 38.

The bottle 13 is placed on a pan 65 on a vertically-slidable rod *p*, mounted in a bracket *q* on the standard 1. Pivoted to the rod *p* is a lever 66, having a fulcrum at *r* and carrying on its opposite end a counterweight 67. Connected to said lever 66 between its fulcrum and the weight is a locking-rod 50, its upper slotted end *s* having free motion on a pin *t* and provided with a nose *u*. A sliding bolt 51 or the like, having an inclined or other suitably-shaped engaging face *v*, is slidable to and from the nose *u*, being urged by a spring 54. The screw-stud 53 on the wafer-carrying device engages a shoulder 52 on the bolt.

Fig. 7 shows a construction of punch which has for its object to cut out from the paper or parchment strip round wafers having serrated edges, such as shown in Fig. 8. It is well known that square wafers, such as are cut by shears and the like from the paper strip in many older and also more recent corking-machines, have the great drawback that when the cork is driven into the neck of the bottle, and therefore when the wafer assumes the cup shape around the cork, irregular folds or creases are formed that are very extensive in the diagonal directions. These creases render the air-tight corking of the bottles difficult if not impossible. In the case of the polygonal or even entirely circular wafers the formation of irregular and sometimes large creases is also not excluded, and, in fact, as has been found by experience, such creases occur with disagreeable frequency, either on account of the irregular shape of the cork or from other causes. By means of the punch shown in Fig. 7 the edges of the circular wafers are provided with radial incisions or serrated in such a manner that a determined direction and uniform dimension are given to the creases. For this purpose the cutting edge of this punch is provided with comparatively large teeth, which are formed on their cutting-surfaces with a

number of smaller teeth. In the external view shown in Fig. 7 the teeth 62 have the form of a right-angled triangle like ratchet-teeth, but are distinguished from the latter by the fact that the radial front surface, the rearwardly and inwardly inclined rear (upper) surface, and the inclined inner surface run to a point d' , so that each tooth has two cutting edges $d' c'$ and $d' b'$, of which the former, which are provided with small teeth 63, serve to cut out the round wafers from the paper strip, while the other cutting edges serve to cut the radial incisions 64 in the wafer and to bend up the edge, as is clearly shown in Fig. 8.

The end of the paper-strip roll on spindle k is passed between the drawing-off rolls 55 56, through the guideway 15 and slot 17, under the cutter, and then between the rolls 18 19. The magazine-tube 42 is filled with superposed corks, the lowermost of which rests on the table 46 in front of the compressing or gripping member 45. The bottle 13 is placed on the pan 65, the counterweight moving the pan and bottle up, so that the lip of the latter is moved into the recess in the under face of the lower removable end 66 of the corking mechanism. Upon rotating the hand-wheel 5 the main shaft 3 is rotated the eccentric 44 on said main shaft draws the element 45 toward the liner 12, thereby moving the lowermost cork that is resting on the table against the projection 47 of the liner, compressing it ready for insertion into the larger end of the conical passage through the liner. The cam 8 on the transverse shaft 4 has by this time rotated, so that it cams down the cap 28 of the cutting mechanism, which contacts with the tubular shank 24' of the cutter, thereby depressing the cutter, as well as the clamping-cylinder 32, these two parts moving in unison by reason of their being held together by the spring 31 between the closed end of the cutter 24 and the pins 32 until the clamping-cylinder engages the paper, when the cutter advances through the paper, this being permitted by the slots 33. The roller 34 then contacts with the end of stem 26 and moves the expelling-disk 25 down to lodge the wafer on the ledge 36 of the circular portion of the forked end of the member 135 if the wafer has not already dropped into position itself. The drum 38 rotates, the roller 60 moving in groove 37, so that the wafer-carrying mechanism 35 135 is moved into the position shown in Fig. 3, with the wafer under the liner 12. The plunger 11 is forced down by rod 10 and crank 9, so that the already-positioned cork is forced through the liner, said liner at the same time being forced down against the tension of the spring 65 and both cork and wafer forced into the neck of the bottle. At the same time that the element 35 is moved forward the screw-stud 53 in this element is moved with it to permit the bolt 51 to be

thrown by its spring 54, the beveled end v taking over the nose u on the rod 50, thus effectually preventing the force exerted on the bottle by the entering cork from depressing the pan 65, that supports the bottle. Before 70 the reduced portion b of plunger 11 has been withdrawn the wafer-carrying plate begins its return movement, the forked end of the plate 135 permitting it to move past the reduced portion, at the same time retracting 75 the locking-bolt 51, so that the pan 65 and weighted lever 66 can be moved to take the bottle 13 off the pan and place another bottle thereon. Before the wafer-cutter comes into operation again the strip 14 has been advanced 80 a step, the upper drawing-rolls 55 56 having made one revolution as well as the lower drawing-rolls 18 19.

Having thus described our invention, what we claim as new therein, and desire to secure by Letters Patent, is—

1. In a machine of the class described, the combination with a main driving-shaft, of stopper-inserting mechanism operated from said shaft, mechanism to cut wafers from a continuous strip operated from the stopper-inserting mechanism, substantially as described.

2. In a machine of the class described, the combination with a main driving-shaft, of stopper-inserting mechanism driven from said shaft, mechanism to cut wafers from a continuous strip operated from the stopper-inserting mechanism, and means at one end of the strip operated by the driving-shaft to impart a step-by-step movement to the strip, substantially as described.

3. In a machine of the class described, the combination with a main driving-shaft, of stopper-inserting mechanism driven from said shaft, mechanism to cut wafers from a continuous strip of material operated from the stopper-inserting mechanism and a wafer-carrying device also operated from said mechanism and timed to carry the wafer from the cutting mechanism under the stopper-inserting mechanism, substantially as described.

4. In a machine of the class described, the combination with a main driving-shaft, of stopper-inserting mechanism driven from said shaft, mechanism to cut wafers from a continuous strip and a wafer-carrying device both operated from the stopper-inserting mechanism, and means operated by the main shaft to draw the continuous strip under the cutting mechanism, substantially as described.

5. In a machine of the class described, the combination with a main driving-shaft and stopper-inserting mechanism driven therefrom, of cutting mechanism to cut wafers from a continuous strip of material and a wafer-carrying device, both operated from the stopper-inserting mechanism; means to draw the strip under the cutting mechanism and means to position the stoppers one at a time.

in the stopper-inserting mechanism and both driven from the main driving-shaft, substantially as described.

6. In a machine of the class described, the combination with a main driving-shaft and stopper - inserting mechanism driven therefrom; of cutting mechanism to cut wafers from a continuous strip of material, a wafer-carrying device, and drawing-off rolls to intermittently draw the strip from the source of supply, all driven from the stopper-inserting mechanism; means to position the stoppers one at a time in the stopper-inserting mechanism and means to draw the strip of material under the cutting mechanism both operated from the main driving-shaft, substantially as described.

7. The combination with a main shaft, a transverse shaft driven therefrom, a crank-operated plunger actuated from the transverse shaft and a magazine for the stoppers, of a liner before the plunger, cutting mechanism to cut wafers from a continuous strip of material, a cam on the transverse shaft to actuate said mechanism, a wafer-carrying device and means to periodically reciprocate the same actuated from the transverse shaft, drawing-off rolls to draw the strip step by step from the source of supply, also driven from the transverse shaft; means to draw the strip under the cutting mechanism, worm-gearing to drive said means from the main shaft, said means timed to draw said strip during the periods of inoperativeness of the drawing-off rolls, a stopper - inserting arm to move the lowermost stopper from beneath the magazine into the liner and at the same time close the

end of the magazine, and an eccentric on the main shaft to operate said arm, substantially as described.

8. In a machine of the class described, the combination with a main driving - shaft; of stopper - inserting mechanism driven therefrom, mechanism to cut wafers from a continuous strip of material operated from the stopper-inserting mechanism, wafer-carrying mechanism, also operated from said stopper-inserting mechanism, a support to hold a bottle in proper relation to the stopper-inserting mechanism, and means to lock said support against movement during the insertion of the stopper and operated by the wafer-carrying mechanism, substantially as described.

9. The combination with a main driving-shaft; of stopper-inserting mechanism operated therefrom, a cutter, cam-operated from the stopper-inserting mechanism, a clamping-cylinder spring connected to the cutter, said cutter capable of moving in unison with the clamp and independently thereof, mechanism to carry the wafer cut under a stopper held in the stopper-inserting mechanism, means to support a bottle, and a lock for said support operated by the wafer-carrying mechanism, substantially as described.

In testimony that we claim the foregoing as our invention we have signed our names in presence of two subscribing witnesses.
